UNITED STATES PATENT OFFICE

130,332

DESIGN FOR A BURIAL VAULT

Dan Trippear, Tacoma, Wash.

Application June 28, 1941, Serial No. 101,779

Term of patent 7 years

To all whom it may concern:

Be it known that I, Dan Trippear, a citizen of the United States, residing at Tacoma, in the county of Pierce, State of Washington, have invented a new, original, and ornamental Design for a Burial Vault, of which the following is a specification, reference being had to the accompanying drawing, forming part thereof.

The figure is a perspective view of a burial vault showing my new design.

I claim:

The ornamental design for a burial vault, substantially as shown.

DAN TRIPPEAR.
